INVENTOR.

Peter J. Thompson,
BY
Mr. H. C. Clegg,
ATTORNEY.

UNITED STATES PATENT OFFICE.

PETER J. THOMPSON, OF BELLEVILLE, NEW JERSEY.

DESIGN FOR A VANITY-CASE, BROOCH, PIN, OR SIMILAR ARTICLE OF JEWELRY.

59,793.

Specification for Design.

Patented Nov. 22, 1921.

Application filed April 5, 1921. Serial No. 458,767. Term of patent 7 years.

To all whom it may concern:

Be it known that I, PETER J. THOMPSON, a citizen of the United States, residing at Belleville, county of Essex and State of New Jersey, have invented a new, original, and ornamental Design for Vanity-Cases, Brooches, Pins, and Similar Articles of Jewelry, of which the following is a specification, reference being had to the accompanying drawing, forming part thereof.

Fig. 2 is an edge view of the article shown in Fig. 1.

I claim

The ornamental design for a vanity case, brooch, pin, or similar article of jewelry, as shown.

PETER J. THOMPSON.
